UNITED STATES PATENT OFFICE

JOHN H. McCANN, OF CHICAGO, ILLINOIS

PROTECTIVE COVER FOR PLUMBING FIXTURES

Application filed March 7, 1930. Serial No. 434,040.

This invention relates to covers for porcelain, marble or vitreous coated plumbing fixtures, and more particularly to coverings that are adapted to be temporarily applied to the fixtures for protecting the same while the building in which they are to be employed is under construction. Many of these fixtures are installed prior to the completion of the plastering or tile-setting in the room, 10 and some times even before the partitions are fixed in position. Under such conditions the fixtures are likely to become damaged by the workmen; accordingly, it is desirable that some form of covering be provided to prevent such injury.

The primary object of this invention is to provide an improved form of protective covering with means to prevent its unauthorized removal from the fixture for insuring the latter against willful abuse, neglect or carelessness during construction work. Another object is to produce an improved protective covering of the character mentioned, designed and arranged for protecting both the inner surfaces and the laterally exposed external surfaces of the fixture. A further object is to produce an improved covering that is simple in construction, light, strong and durable, and capable of being used over and over again. It consists in certain features and elements of construction as herein shown and described, and as indicated by the claims.

In the drawings:

Figure 1 is a front elevation of a pedestal type of lavatory fixture provided with a covering embodying the present invention.

Figure 2 is a side elevation of the same.

Figure 3 is a top plan view of my protective cover applied to a closet bowl.

Figure 4 is a rear elevation of the same.

Figure 5 is a bottom plan view of another form of protective covering applied to a pedestal type of lavatory fixture.

Figure 6 is a side elevation of the same.

Referring now in detail to the drawings, the fixture illustrated in Figures 1 and 2 is a pedestal type of lavatory, 1, having a supporting base or pedestal, 2, mounted on the floor. The bowl portion of the fixture is

shown as of rectangular form and is encased by a protective covering, 3, formed of any suitable rigid material such as wood or sheet metal, which is constructed as a rigid box-like structure having a top portion, 4, and laterally depending flanges, 5, extending on all four sides of the fixture. Since fixtures of this character are frequently equipped with the usual plumbing fittings, namely, faucets and drain plugs, before construction work in the building is completed, it is necessary to make some provision to accommodate and enclose these fittings. Accordingly, the depending flanges, 5, and top, 4, are dimensioned to afford sufficient clearance for these fittings, as may be seen in Figure 2. To properly support this box-like covering on the fixture with the top out of contact with the fittings, any suitable stop may be secured on the inside of the covering, and for this purpose I employ angle clips indicated at 6, secured to the inside of the covering, and herein shown attached to the rear flange, 5, and to the top, in a manner to engage with the horizontal upper surface of the fixture.

It will be apparent that by reason of this construction, the covering may be removed only in an upward direction. To prevent unauthorized removal of the cover, it is locked to the fixture by a pair of flexible tie members, 8, herein shown as flexible chains each rigidly secured at one end to one depending flange of the covering and extending rearwardly beneath the bowl portion of the fixture and having their other ends connected to a shackle, 9, on the opposite flange, by means of a padlock, 10.

It is apparent that these coverings are necessarily designed with a reasonable amount of clearance which will permit the cover properly to be shifted somewhat laterally on the fixture. Accordingly, to prevent any abrasion of the finished under surface of the fixture by the portion of the chains that comes in contact with the bowl proper, I encase these portions of the chains with a flexible sheath, 11, of rubber, leather, or other suitable material. And the laterally depending flanges, 5, together with the under sides of the clips, 6, that engage the top of the fixture may be pro-

vided with suitable lining (not shown) such as felt, to protect the engaged surface of the fixture against abrasion.

Figures 3 and 4 illustrate a form of protective covering applied to a closet bowl fixture indicated generally at 15. The covering for such a fixture includes a flat top portion, 16, and rigid depending flange portions, 17, at opposite sides connected together by a rigid flange portion, 18, at the front. These flanges are each formed at their lower extremities with rigid inwardly projecting portions, 17^a and 18^a, respectively, which are dimensioned, as may be seen in Figure 4, to come in close proximity to the curved under surface of the bowl proper of the fixture so that the covering as a whole cannot be removed from the fixture by withdrawal in an upward direction, but may only be placed on and removed from the fixture by movement in horizontal direction from the front of the fixture.

The rear edge of the top portion, 16, is recessed at 19, to accommodate the flush pipe, 20, and thus permit the covering to be properly positioned. The cover as a unit is held against unauthorized removal by a flexible chain, 21, connected to the rear edge of one of the inward projecting flange portions, 17^a, and trained around the rear of the fixture, with the other end connected by a padlock, 22, to the rear end of the other inwardly extending part, 17^a, of the flange. To prevent the rear of the fixture from damage or abrasion by contact of the chain, 21, the latter is preferably encased in a sheath, 23, of a suitable flexible material.

Figures 5 and 6 illustrate a modified form of cover, 25, for a pedestal type of lavatory, 26, having a support, 27, mounted on the floor. In this construction the covering is formed as a rigid downwardly open box-like structure having a top portion, 28, and rigid vertically depending flanges, 29, on all four sides, and hingedly connected to the lower edges of each of said flanges, 29. Slightly below the lower edges of the lavatory bowl proper is a supplemental flap, 30, adapted to be swung inwardly toward the support, 27, of the fixture. Each of the hinged flaps, 30, is provided on its inner side with an eyelet, 31, adjacent its longitudinal center, and trained through these eyelets is a flexible tie member, 32, herein shown as a chain. It will be apparent that when the chain is drawn taut, 55 these supplemental hinged flap portions, 30, will be caused to move inwardly with a portion extending inwardly beyond the edges of the bowl, as seen in Figure 6. In such a position of adjustment the ends of the chain are secured together by a padlock, 33, for preventing unauthorized removal of the protective covering in a lateral or upward direction.

It will be understood that in all of the protective coverings for the various fixtures illustrated in Figures 1 to 6, the interior surfaces

of the coverings are lined with suitable material such as felt so as to protect the finished surface of the fixtures against injury by abrasion such as might occur by placing on or removing the covering from the fixture, or due to the limited amount of movement even when it is locked in place thereon.

I claim:

1. In combination with a plumbing fixture including an upwardly open body, a protective cover including laterally depending flanges with locking means on said flanges engaging the under portion of the body to prevent unauthorized removal of said cover.

2. In combination with a plumbing fixture including a body having upwardly and laterally exposed surfaces and a part extending downwardly from the body into connection with a fixed part of the building structure in which the fixture is installed, a protective cover including a main portion for the upper surface of the fixture and laterally depending flanges for enclosing said laterally exposed surfaces; together with locking means carried on the flanges and engageable with the downwardly extending part of the fixture for precluding unauthorized removal of the cover.

3. In the combination defined in claim 2, one or more of said flanges being provided with an inwardly extending portion adapted to engage the lower edge of the body to prevent upward removal of said cover.

4. In combination with a plumbing fixture including a body having an upwardly open cavity and a downwardly exposed surface, a temporary protective cover dimensioned to serve as a closure for the cavity, and a tie member connected to the cover and extending under the downwardly exposed surface, together with locking means securing the tie in such position for preventing unauthorized removal of the cover, said cover being completely removable upon release of said locking means.

5. In combination with a plumbing fixture including a body having an upwardly open cavity and upwardly and laterally exposed surfaces, a protective cover including a main portion for the upper surface serving as a closure for the cavity, a plurality of laterally depending flanges secured to the main portion and arranged for completely encasing said laterally exposed surfaces; together with locking means engageable with the body of the fixture adapted to prevent unauthorized removal of the cover.

6. In combination with a plumbing fixture including a body having upwardly and laterally exposed surfaces, a protective cover including a main portion for the upper surface of the fixture and a plurality of laterally depending flanges hinged thereto to encase said laterally exposed surfaces, said flanges being adjustable inwardly to oblique position, and

locking means for securing said flanges in such oblique position adapted to prevent unauthorized removal of said cover.

7. In combination with a plumbing fixture including an upwardly open cavity and laterally and downwardly exposed surfaces, a temporary cover including a main portion for the cavity, and a plurality of depending flanges connected to the main portion and arranged for overlapping the laterally exposed surfaces of the fixture, said flanges each having a lower portion extending obliquely inwardly for engaging the downwardly exposed surface of the fixture for preventing removal of the cover in an upwardly direction, and locking means carried on said flanges and engageable with the exposed surface of the fixture for precluding the unauthorized removal of the cover.
8. In combination with a plumbing fixture including an upwardly open cavity and laterally and downwardly exposed surfaces, a temporary cover including a main portion for the cavity and rigid depending flanges connected to the main portion, encasing the front and sides of the fixture, the lower portions of the flanges extending obliquely inwardly for engaging the downwardly exposed surface of the fixture for preventing removal of the cover in an upwardly direction, and locking means connected to the rear ends of said side flanges and engageable with the rearward end of the fixture for preventing unauthorized removal of said cover.

35 In testimony whereof, I have hereunto set my hand at Chicago, Illinois, this 24th day of February, 1930.

JOHN H. McCANN.
